ATTORNEY

UNITED STATES PATENT OFFICE.

GEORGE L. PERRINE, OF ST. JOHNS, OREGON.

FIREPLACE.

1,049,262.

Specification of Letters Patent. Patented Dec. 31, 1912.

Application filed September 18, 1910. Serial No. 582,408.

To all whom it may concern:

Be it known that I, GEORGE L. PERRINE, a citizen of the United States, and a resident of St. Johns, county of Multnomah, State of Oregon, have invented an Improved Fireplace, of which the following is a specification.

My invention is an improvement in that class of fireplaces in which the side walls converge to the rear and a horizontal ledge or step extends between such walls.

My invention is embodied in the construction, arrangement, and combination of parts hereinafter described and particularly indicated in the claim.

I have embodied this principle of construction in the fireplace illustrated in the accompanying drawings, in which—

Figure 1 represents a vertical cross-section 20 of my improved fireplace; Fig. 2 is a horizontal cross-section approximately taken on a line A—A of Fig. 1.

Referring now more particularly to the construction of my fireplace, *a* represents a portion of the top outer wall, and *b* the throat to the chimney. The rear is concaved approximately as shown. A ledge *d* is arranged at the apex of the angle of the converging side walls *f* and *g* and at the rear 30 of the hearth *l*, the ledge having a vertical front wall. It will be noted that a considerable space *e* is thus provided between the converging walls and above the ledge *d*. By this arrangement, air is prevented from 35 entering at a point below the ledge, but passes along the converging side walls and up over the ledge *d* in order to reach the

space *e*. In other words, when a fire is built in the grate *h*, the air from the front will enter through the bottom of the grate 40 and thence along the rear surface, *C*, to the throat of the chimney, while the air entering at *i*, that is, in the upper part of the fireplace will drive the flames and products of combustion back into the recess *e* and compel them to take the course indicated by the arrows. The fuel-supporting member or grate *h* extends between the side walls *f*, *g*, or the entire length of the ledge, so that no air can rise over the latter without first passing 45 through the zone of combustion.

Practical use of this invention has demonstrated its superiority over fire-places of the ordinary construction and that a maximum calorific effect is produced with a minimum 50 combustion of fuel.

I claim:

An improved fire-place formed of vertical side walls converging to the rear, the rear of the fireplace being gradually curved forward from the bottom upward, a horizontal ledge extending between the lower rear portions of said side walls, and a fuel-supporting member situated in front of said ledge and extending the length of the latter between the side walls, and thereby excluding the entrance of air to the space above said ledge without having passed through the zone of combustion, as described.

G. L. PERRINE.
